UNITED STATES PATENT OFFICE

CHRISTOPHER EDMUND GERVASE BAILEY, OF LONDON, ENGLAND, ASSIGNOR, BY MESNE ASSIGNMENTS, TO RADIO CORPORATION OF AMERICA, OF NEW YORK, N. Y., A CORPORATION OF DELAWARE

HIGH FREQUENCY AMPLIFIER

Application filed September 7, 1929, Serial No. 391,018, and in Great Britain September 27, 1928.

The present invention relates to high frequency amplifiers. It is well known that when the selectivity of a high frequency amplifier for use in the amplification of wireless telephony signals is made sufficiently great to eliminate unwanted signals, the amplification at frequencies on both sides of the carrier frequency is less than that at the carrier frequency itself and decreases rapidly as the difference from the carrier frequency increases. Assuming that, for the satisfactory reproduction of music or speech, frequencies from 25 to 10,000 cycles per second are required to be received with sensibly equal intensity, it is necessary that the high frequency amplifier should amplify equally all frequencies lying between $N-10,000$ and $N+10,000$ cycles per second where N is the carrier frequency.

As the selectivity of the amplifier is increased the higher audio frequencies are cut out altogether and the intermediate frequencies are less amplified than the low frequencies with consequent ill effect upon the quality of the reproduced sounds.

The present invention is concerned with improved circuit arrangements whereby the above effects can be reduced. According to the present invention a circuit arrangement for amplifying modulated high frequency carrier oscillations comprises two circuits tuned to the carrier frequency to be amplified, one of said circuits being adapted to reduce, in effect, the amplification of the circuit arrangement over a band of frequencies on either side of said carrier frequency. The latter circuit is less heavily damped than the other circuit.

The invention will be described by way of example, with reference to the accompanying drawing, as applied to a high frequency amplifier in which the anode circuit is tuned. The valve V_1 is a high frequency amplifier having input terminals 1 which may be connected to the receiving aerial circuit. In the anode circuit of the valve V_1 is a tuned circuit 2, the anode current being fed to this valve through the inductance coil of this tuned circuit. The anode of the valve V_1 is connected to the grid of the valve V_2 , which

may be a detector valve, through an inductance 3 and a condenser 4. An inductance 5 is closely coupled to the inductance 3 and a variable condenser 6 is connected in parallel with the two inductances 3 and 5 in series. It is essential that some resistance should be provided in the circuit, 3, 5, 6 and it is sometimes found necessary to add a small series resistance 7. The damping of this circuit 3, 5, 6 must, however, be less than that of the circuit 2. It will be noted that the circuit 2 is damped by the associated valve.

In operation, the two tuned circuits 2 and 3, 5, 6 are adjusted by means of the variable condensers to resonate at the frequency of the carrier to be received, and if the values of the components of these circuits have been suitably selected the overall amplification for any given degree of selectivity will be found to be much more uniform over the important frequency band than would be the case if the second tuned circuit, between the anode of one valve and the grid of the next, were not included. The effect of this tuned circuit is to reduce the amplification of the frequencies in the neighborhood of the carrier frequency in relation to the amplification of the frequencies further from the carrier frequency.

It will be understood that the invention is not limited to the case in which a tuned anode circuit is used, the invention being applicable to circuits embodying other forms of couplings, for example, high frequency transformer coupling. The controls of the two condensers may if desired be mechanically coupled in order to ensure that the two tuned circuits are always tuned to the same frequency but preferably, however, the circuit is used as an intermediate circuit amplifier in a super-heterodyne receiver in which the intermediate frequency is fixed and the heterodyne frequency is variable. In such a circuit the adjustment of the two condensers can be made once and for all and the selectivity and the shape of the amplification curve will then remain constant whatever the frequency of the carrier wave to be received may be.

I claim:

1. A circuit arrangement for amplifying

modulated high frequency carrier oscillations comprising two circuits tuned to the carrier frequency to be amplified and arranged successively to receive said oscillations, the second one of said circuits being damped whereby it is adapted to reduce in effect the amplification of the circuit arrangement over a band of frequencies on either side of said carrier frequency, and the first of said circuits being damped to a greater degree than the second one of said circuits.

2. A circuit arrangement for amplifying modulated high frequency carrier oscillations including two thermionic valves each having an anode circuit and a grid circuit, two circuits tuned to the carrier frequency to be amplified, one of said circuits being disposed in parallel with the anode circuit of one of said thermionic valves and being thereby damped, the other of said circuits including a damping resistance providing a lesser degree of damping than that applied to said parallel circuit and further including two closely coupled inductances one of which is disposed in series between the anode circuit of said one of said valves and the grid circuit of the other of said valves.

3. In a high frequency amplifier, the combination of a tuned circuit, a thermionic valve connected therewith whereby said circuit is damped, a second tuned circuit, said circuit including an inductance and means for damping said circuit to a less degree than the first named circuit, a second inductance in said second named circuit closely coupled with the first named inductance, and a second thermionic valve having a grid connected with said circuit at a point between said inductances.

4. In a high frequency amplifier, the combination of a tuned circuit responsive to a predetermined frequency, a thermionic valve having an anode connected with said circuit whereby said circuit is damped, a second tuned circuit responsive to said predetermined frequency, said circuit including an inductance and a resistance having a value such that said circuit is damped to a less degree than the first named circuit, a second inductance in said second named circuit closely coupled with the first named inductance, a thermionic valve having a grid, and means providing a connection from said first named circuit through said first named inductance with the said grid.

In testimony whereof I have signed my name to this specification.

CHRISTOPHER EDMUND GERVASE BAILEY.
